DESIGN FOR A BROOCH OR SIMILAR ARTICLE OF JEWELRY

Edmond Foret, New York, N. Y., assignor to Cartier, Inc., New York, N. Y., a corporation of
New York

Application March 26, 1941, Serial No. 99,906

Term of patent 3½ years

To all whom it may concern:

Be it known that I, Edmond Foret, a citizen of France, residing at New York city, in the county and State of New York, have invented a new, original, and ornamental Design for a Brooch or Similar Article of Jewelry, of which the following is a specification, reference being had to the accompanying drawing forming part thereof.

Figure 1 is a front elevational view of a brooch or similar article of jewelry showing my new design; and

I claim:

The ornamental design for a brooch or similar article of jewelry, as shown.

EDMOND FORET.
